[57] CLAIM

The ornamental design for a handle for walking stick or
the like, as shown and described.

DESCRIPTION

FIG. 1 is a front elevational view of a handle for walking
stick or the like showing my new design;

FIG. 2 is a rear elevational view thereof;

FIG. 3 is a side elevational view thereof;

FIG. 4 is a side elevational view of the side opposite
that shown in FIG. 3; and

FIG. 5 is a bottom plan view thereof.

FIG.1.

FIG.2.

FIG.3.

FIG.4.

FIG.5.
